(57) **CLAIM**

I claim the ornamental design for a combined race car hood mouse pad and drink coaster, as shown and described.

DESCRIPTION

FIG. 1 is a perspective view of a combined race car mouse pad and drink coaster of the present invention;

FIG. 2 is a front elevational view thereof;

FIG. 3 is a left side elevational view thereof;

FIG. 4 is a rear elevational view thereof;

FIG. 5 is a right side elevational view;

FIG. 6 is a top plan view thereof; and,

FIG. 7 is a bottom plan view thereof.

The broken line showing of the computer mouse and hood locks is for illustrative purposes only and forms no part of the claimed design.
